CLAIM

The ornamental design for a set of earphones and charging box as shown and described.

DESCRIPTION

FIG. 1 is a perspective view of a set of earphones and charging box showing my new design;

FIG. 2 is a perspective view of a charging box of the set of earphones and charging box, shown separately for ease of illustration and in an opened configuration;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of a charging box of the set of earphones and charging box, shown separately for ease of illustration and in a closed configuration;

FIG. 11 is a perspective view of earphones of the set of earphones and charging box, shown separately for ease of illustration;

FIG. 12 is another perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof; and,

FIG. 18 is a bottom plan view thereof.

The dash-dash broken lines in the drawings depict portions of the set of earphones and charging box that form no part of the claimed design.
